UNITED STATES PATENT OFFICE.

EDWARD Y. MOORE, OF CHICAGO, ILLINOIS.

CAR-DOOR HANGER.

SPECIFICATION forming part of Letters Patent No. 308,916, dated December 9, 1884.

Application filed November 7, 1881. (No model.)

To all whom it may concern:

Be it known that I, EDWARD Y. MOORE, residing at Chicago, in the county of Cook and State of Illinois, and a citizen of the United States, have invented a new and useful Improvement in Car-Door Hangers, of which the following is a full description, reference being had to the accompanying drawings, in which—

Figure 1 is a side elevation of a portion of a car-body and door, showing the devices for hanging or supporting the door, so that it can be easily opened and closed. Fig. 2 is a vertical section through the door on line *w w* of Fig. 1; Fig. 3, a longitudinal section through the door on line *x x* of Fig. 1; Fig. 4, an enlarged detail showing the corner of the door in elevation, with the back portion or plate of the frame or support for the roller thereon; Fig. 5, an enlarged detail showing an edge view of the corner of the door, with the frame or support, roller or wheel, carrying-plate, and operating-lever thereon; Fig. 6, an enlarged detail, being an inner face view of the outer portion or plate of the roller frame or casing; Fig. 7, an enlarged detail, being a side elevation of the roller-plate and roller; Fig. 8, an enlarged detail, being a vertical section through the corner of the door, the frame or casing for the roller, with the roller-plate and roller in elevation.

It is customary to support or hang car-doors between stationary tracks or guide-rails located above and below the door on the side of the body of the car, the door having hangers and guides or forks which pass over the tracks or guide-rails and retain the door in place. This method of supporting or hanging such doors renders the opening and closing of the door exceedingly difficult, requiring in some instances the exertion of considerable force in order to move the door. To overcome this difficulty such doors have been supported or hung on a stationary track or guide-rail by means of rollers or wheels and suspending straps or hangers, the rollers or wheels resting on the tracks or guide-rails at all times; but this plan is not feasible, on account of the constant jar of the car when in motion, which jar opens the door when closed, or vice versa, by reason of the rollers or wheels running easily on the track or guideway, there not being

sufficient frictional contact to prevent this result.

Sliding doors have heretofore been mounted upon bed-rollers pivoted to vertical slides, and these latter have been controlled by a pair of levers, in turn actuated by a horizontal hand-lever for lifting the door, as shown and described, for instance, in the patent of Waterhouse, No 101,194, March 22, A. D. 1870.

It will be seen that my combination of devices, operating as a car-door hanger, is such that when the vertical hand-lever is moved in the direction desired for moving the door that the door is lifted, and that a continuation of pressure in the same direction serves also to slide the door, in that respect differing from the aforesaid prior horizontal hand-lever, which requires a downward pressure for lifting the door, and a separate sidewise application of force for sliding the door. Other prior doors initially lifted prior to sliding have involved the use of a vertical hand-lever, which, like mine, required pressure only in the direction in which the door was to be moved; but, unlike mine, said last-named prior lever was itself one of the roller-levers, and it was coupled to a similar vertical roller-lever, both of which had a short cross piece or shoe, which, by being rocked in either direction upon its end supports served to lift the door—as, for instance, as shown and described in the Letters Patent to Earle, reissued April 19, 1881, No. 9,679.

The object of this invention is to obviate objections heretofore existing in the use of rollers or wheels for supporting or hanging car-doors, and to support or hang the door so that it will ride or run easily in opening and closing, and at the same time prevent or obviate any liability of the door to open or close of its own accord; and its nature consists in providing a roller or wheel which can be brought into contact with the track or guide rail as the door is to be opened or closed, and be out of contact therewith when the door is at rest, combined with a stop or rest located on the frame or support for the roller to maintain the proper relation between the roller and guideway or track under any circumstances; in providing a stop or rest located and arranged on a frame or support for a

- roller or wheel mounted on a sliding plate or support located in a frame or casing, and said lever and connections for actuating the roller by the act of opening or closing the door and 5 maintaining a coacting relation between the track, the roller, and the stop or rest; in providing a lever or arm pivoted to the door and connected with the sliding plates or other devices carrying the rollers or wheels for bringing the rollers or wheels in contact with the track or guideway as the door is opened or closed, and in the several parts and combinations of parts hereinafter set forth and claimed as new.
- 15 In the drawings, A represents the body of a car; B, the door; C, the support for the lower guideway or track; D, the support for the upper guide-strip or track; a, the sliding plate or support; b, the wheel or roller; c c', the frame or outer casing; d, the engaging-pins; f, pivots of the levers or links e to the frame or casing c; g, the lever for operating the levers or links e e'; h, the anti-friction roller on which the ends of the levers or links 20 e e' rest; i i', the handles or stirrups on the lever g; j, the guard or stop-plate to which the lever g is pivoted; k, the lower guide rail or track; l, the upper guide strip or track; m, the guides or forks.
- 25 The body A of the car and the door B, with the strips or rails C D for the guide-strips or tracks, may be of any of the usual and well-known forms of construction and arrangement, the guide-rails being secured to the body of the 30 car above and below the door, and being provided with guide-strips or tracks k l of the form shown, or of other form suitable for rollers or wheels to travel on, and for the guides or forks m to pass thereover.
- 35 In the form shown in Figs. 1 to 8, inclusive, a roller, b, of any suitable form of construction is mounted on a trunnion or journal-pin formed with or attached to a plate, a, which plate is located in a recess or chamber formed 40 in a casing or frame, c c', the frame or casing being so formed as to leave a recess or chamber adapted to receive a plate, a, and the wheel or roller b and allow vertical play. As shown, this frame or casing is formed in two 45 sections or parts, c c', one of which, c', has a recess or chamber for the wheel or roller b, and is located between the plate a and the face of the door, and the other, c, has a chamber or recess for the end of the arm or lever 50 by which the plate a is moved, and is located outside of and around the plate a, a sufficient space being left between the sections or parts c c' for the reception of the plate a. These sections or parts c c' are attached to the door 55 by means of screws, bolts, or otherwise, and when in position their lower ends project below the edge of the door a sufficient distance for the passage of the guide-rail or track k between them, so as to be in line with the 60 roller or wheel b, as shown in Fig. 2. These recesses for the passage of the guide-rail or

track in the lower end of the casing or frame form at their terminus a stop or rest, which, when the door is down, comes in contact with and rests upon the track or guide-rail, forming 70 a support for the door when lowered, and this stop or rest may be formed by the terminus of the slot or recess on both sides or only on one side, and in either event it will be seen that the stop or rest and the track and roller 75 must be always in the same coacting relation, for the reason that the roller and the stop or rest, being located or arranged on the same frame or support, must move together and in the same relation to each other. At the upper end of the plate a in this form of construction are lugs or pins d, formed with or secured to the plate, and between these lugs or pins d one end of the link or lever e passes, which lever is attached to the frame or plate c by a 80 pin or pivot, f, and its other end passes through the loop or stirrup i on the lower end of the lever g. This end of the arm or lever e, as shown, is slightly curved, and this curved portion has its under face or edge resting on 85 or in contact with an anti-friction roller, h, pivoted to the lever g between the face of the lever and the face of the strap or stirrup i, as shown in Fig. 1.

Two rollers or wheels are used, one on each 90 side of the door, and each carried by a plate, a, located in a frame or support, so as to move vertically, and connected at their upper ends with the levers or arms e, and these levers or arms e have their outer or free ends pass 95 through the loop formed by the strap or stirrup i over the anti-friction roller h, so that the ends of both levers will be operated simultaneously by the roller h.

The lever g may be formed as shown, or in 100 some other suitable manner. This lever is pivoted at or near its center to the plate j, secured by screws or otherwise to the face of the door B, and this plate j, as shown, has a recess to receive the body of the lever, the sides 110 of which are beveled or inclined toward the center, and form stops to limit the throw of the lever. As shown, the upper end of the lever has a stirrup or strap, i', which forms a handle, which can be grasped by the hand to 115 move the lever, but some other device may be used for this purpose.

It will be understood that the strap or stirrup i, at the lower end of the lever g, also forms a handle by which the lever can be operated to open and close the door.

The operation is as follows: When the door is to be opened or closed, the lever g is pushed or pulled, as required, to move the door in the desired direction to open or close it, the 125 operator taking hold of the strap or handle i or i' for this purpose. The movement of the upper end of the lever in one direction carries its lower end in the opposite direction by reason of the central pivot, and this movement of the lower end of the lever causes it to 130 describe an arc of a circle, the movement be-

ing the same no matter in which direction the end of the lever moves. This movement in an arc of a circle lifts or raises the outer or free ends of the arms or levers *e* through their contact with the roller *h*, depressing the inner ends of such levers, and through their connection with their respective plates *a* throw such plates down, forcing the rollers *b* onto the track *k*, and raising the door, so that it 5 rides free and clear on the rollers or wheels, when it can be rolled forward or back, as required, to close or open the door.

The construction and operation of devices just described are intended for use where the 15 track is below the door and the rollers are at the lower end of the door.

In place of using a sliding plate, *a*, in the form of construction shown in Figs. 1 and 2, where the lever or arm *e* is in two parts, such 20 levers or arms might be located lower down on the door, and the rollers or wheels journaled or mounted on their inner ends within 25 the casing or frame, so that as such inner ends are depressed by elevating the outer or free 30 ends the rollers or wheels will be brought into contact with the track or guide-rail, or the inner end of each lever or arm might be turned or bent down, and the roller or wheel be journaled or mounted on the end of such turned 35 or downward extended portion, and be brought into contact with the track or guide-rail by raising the outer or free end of each lever or arm; and it will be readily seen that various other forms of supporting these rollers 40 or wheels could be used in connection with a lever or other device located on the car-door, by which the act of opening or closing the door will bring the rollers or wheels into engagement or contact with the track or guide-rail. By this method of supporting or hanging 45 the door it will be seen that when the door is at rest, in either its open or closed position, the rollers or wheels will be out of contact with the track or guide-rail, the weight of the door throwing the rollers or wheels up as soon as the lever *g* is released, and that 50 when the rollers or wheels are not engaged with the track or guide-rail the door rests on its bearings and is immovable to the same extent as if rollers or wheels were not used.

The bearings on which the door rests may be formed by the end or face of each frame at the terminus of the slot which receives the track or guide-rail, or such bearings may be 55 formed of independent blocks suitably attached to the end of the door and adapted to rest on the track or guide-rail when the door is dropped down, provided that such independent supports are attached or connected 60 with the roller frame or support, so as to be virtually a part thereof, and be maintained in the same relation to the rollers in all circumstances. By thus making the rollers and the stops or rests for the door coacting it will be

seen that these two parts maintain their same 65 relative position irrespective of any shrinking of the door or dropping or raising of the track, by which means, when the door is at rest, the rollers will be clear of the track and the door will be immovable by reason of engagement of the rests or stops with the track, and this feature of maintaining the same relation between the rests or stops and the roller is essential where it is desired to have the door remain immovable when the rollers are 75 not engaged with the track, and to insure the engagement of the rollers with the track when the door is to be moved.

What I claim as new, and desire to secure by Letters Patent, is—

1. The combination, with the car-door, its rollers, and rail, of the horizontal roller-levers, the vertical hand-lever, and means by which the vertical lever is connected with the inner ends of the horizontal levers, substantially as 85 described.

2. In a car-door hanger, a roller or wheel operated through connecting devices by the act of opening and closing the door, in combination with a stop or rest connected with the roller-support and coacting with the roller for opening and closing the door readily and holding it stationary while at rest, substantially as described.

3. In a car-door hanger, a roller or wheel 95 carried by a sliding plate operated through connecting devices by the act of opening and closing the door, in combination with a stop or rest connected with the roller-support and coacting with the wheel or roller for bringing 100 the roller or wheel into engagement with the track or guide-rail, and keeping the wheel or roller from engagement with the track or guide-rail when the door is at rest, substantially as and for the purpose set forth.

4. In a car-door hanger, a sliding plate, *a*, carrying a wheel or roller, *b*, and a stop or rest connected with the roller-support and coacting with the roller, in combination with a lever located on the car-door and connected 110 with the sliding plate, whereby the wheel or roller will be brought into engagement with the track or guide-rail as the door is opened or closed, and will be clear of such track or guide-rail when the door is at rest, substantially 115 as and for the purposes specified.

5. In a car-door hanger, a sliding plate, *a*, carrying a roller or wheel, *b*, and a stop or rest connected with the roller-support and coacting with a lever, *g*, pivotally attached to 120 the door at its center, and a connecting arm or link, *e*, for depressing the plate and bringing the roller or wheel into contact with the track or guide-rail, substantially as specified.

EDWARD Y. MOORE.
